UNITED STATES PATENT OFFICE.

JOHN VON KANEL, OF AKRON, OHIO.

MOP-WRINGER.

SPECIFICATION forming part of Letters Patent No. 707,235, dated August 19, 1902.

Application filed July 3, 1901. Serial No. 67,013. (No model.)

To all whom it may concern:

Be it known that I, JOHN VON KANEL, a citizen of the United States, residing at Akron, in the county of Summit and State of Ohio, have 5 invented certain new and useful Improvements in Mop-Wringers, of which the following is a specification.

My invention relates to devices for squeezing the surplus water from the mop after immersion in a pail of water, and particularly 10 to that class of wringers that are adapted to be removably attached to the side of the pail.

The objects of my invention are to provide 15 a device of the class described which may be manufactured at a minimum cost and that is effective in operation.

In the drawings, Figure 1 is a side view in 20 elevation of the mop-wringer open to receive the mop after immersion; Fig. 2, a front view, the wringer being in the position it assumes when emitting the water from the mop; and Fig. 3, a vertical longitudinal section showing the wringer attached to a pail, and Fig. 4 a detail view of the operating mechanism.

Referring to the drawings, in which similar letters of reference indicate like parts throughout the several views, the sides of my wringer are designated by A and the front 30 piece by B, which is attached to the side pieces by any suitable means. The sides A and front B are indiscriminately perforated, as shown at C C, to permit the egress of water from the mop while being pressed, as herein- 35 after described. The sides A have downwardly-projecting portions a a and near the ends thereof inwardly-projecting lugs or teats a' a'.

The back D is held between two strips d d, 40 perforated near their bottom ends at d' d' to receive the lugs or teats a' a', while the bottom D' is fastened between said strips d d and to the bottom edge of the back D and serves to limit the downward movement of 45 the mop when the wringer is open to receive it as well as act as a water-guide when the mop is being pressed.

Journalized in the side pieces A is a shaft E, on the center of which is fixed a cam F, adapted to bear against the back piece D and press 50 the mop between the front B and said back piece D. The edge of the cam F that bears

against the back piece D has an outwardly-flaring edge f, while the back piece D has attached thereto a cleat G with a slot g, shaped 55 to receive the flaring edge f above described, the whole being similar in construction to a dovetail joint, except that the parts are made to not fit snugly.

The purpose of the construction last above 60 described is to afford means for opening the receptacle after the mop is pressed.

H represents a lever fastened by any suitable means to the end of the shaft E.

I I represent slots cut into the bottom of 65 the side pieces A A to hold the device on a bucket.

The operation is as follows: Place the device on the edge of the bucket by means of the slots I I. After wetting the mop place it 70 in the receptacle, and by swinging the lever toward the interior of the pail the cam F will push the back D against the front B, squeezing the water out through the holes C into the bucket. When the mop is wrung 75 out, push the lever outwardly and the back D will be returned to its normal position and the mop may be removed.

I do not wish to be limited to the exact construction shown in the drawings or described 80 herein, as the same may be altered somewhat without departing from the spirit of my invention.

Having thus described my invention, what I claim is—

1. In a mop-wringer, a perforated box portion, an imperforate presser portion pivoted to said box portion, a water-guide fixed to said presser portion, and a cam adapted to reciprocate said presser portion, substantially 90 as shown and described.

2. In a mop-wringer, a box portion, a presser portion pivoted thereto, a water-guide secured to said presser portion, a cam adapted to oscillate said presser portion, a flaring edge on 95 said cam, and a dovetail slot on said presser portion to receive the flaring edge on the cam, substantially as shown and described.

3. In a mop-wringer, a perforated box portion, an imperforate presser portion pivoted 100 thereto, a water-guide secured to said presser portion, a cam to oscillate said presser portion, a flaring edge on said cam, and a dovetail slot on said presser portion to receive the

flaring edge on the cam, substantially as shown and described.

4. In a mop-wringer, a perforated box portion, a rock-shaft journaled therein, a presser-board pivoted in said box portion, a water-guide on the lower edge of said presser-board, a cam keyed to said rock-shaft having a flaring edge, and a dovetail slot on the back of said

presser-board to receive the flaring edge on the cam, substantially as shown and described. 10

In testimony whereof I hereto affix my signature in the presence of two witnesses.

JOHN VON KANEL.
